UNITED STATES PATENT OFFICE.

CHARLES M. EBERLING, OF CLEVELAND, OHIO.

CONCRETE MIXER.

Application filed April 23, 1927. Serial No. 186,137.

This invention relates to concrete mixers and has for its objects the provision of a new and improved batch mixer; the provision of a batch mixer having new and simplified discharging arrangements; the provision of a batch type mixer having measuring devices of maximum simplicity for the purpose of gauging the amounts of the different solid ingredients; the provision of a mixer having improved and simplified provisions for filling and emptying; the provision of a concrete mixer of such simplicity as to insure the production of satisfactory concrete with the most ignorant or inattentive laborers; the provision of a device of this character having a new and improved arrangement and relation of mixing knives; the provision of a concrete mixer having improved and simplified structural features; while further objects and advantages of the invention will become apparent as the description proceeds.

In the drawings accompanying and forming a part of this application I have shown a simple physical form in which my inventive ideas are embodied, although it will be understood that these drawings are intended to be merely illustrative of the principles of my invention and not of all practical means of embodying the same. Figs. 1 and 2 are perspective views of my improved mixer; Fig. 3 is a transverse sectional view, and Fig. 4 a longitudinal sectional view; and Fig. 5 is an enlarged detail view of the plate securing means.

For the frame of my machine I have shown a pair of cast-iron uprights 1-1 connected by longitudinal bars 2-2 and by the semi-cylindrical bottom 3 of the mixing trough or receptacle a seat 4 for this trough being carried by each of the uprights. Also carried by each of the uprights is a journal box 5 in which is mounted a horizontal shaft 6 provided at one end with an operating gear 7 which meshes with a driving pinion (not shown) carried by the counter shaft 8 and driven by the pulley 9 loosely journaled on said countershaft and adapted to be secured operatively thereto by means of the clutch 10. The trough 3 terminates at one side not far from the level of the shaft 6 as indicated at 8 in Fig. 3, but the corresponding portion 12 of said trough on the opposite side of the shaft, instead of terminating it is extended upwardly and outwardly as illustrated at 13 to form the bottom of a slant-

ing hopper. The two end walls of the mixer are defined by upright metal plates 14 which are suitably joined to the bottom plate 13 along their meeting line, and also to the curved portion of the trough 3, and the plates 13 and 14 are preferably terminated at the same height as indicated at 15 in Fig. 1. To the opposite side of the machine I provide a vertically movable gate 16, slidably mounted in angle iron guideways 17 carried by the end walls 14. Also carried by these walls are a pair of brackets 18-18 in which is journaled a shaft 19 connected by loose chains 20-20 with the lower portion of the gate 16, one end of the shaft being provided with a crank 20 by which the chain can be wound on the shaft so as to raise the gate.

Interposed between the hopper portion 75 and the mixing trough on the side opposite said gate 16 is a second vertically slidable gate 21 movably supported by means of angle-iron guides 22 and likewise connected by chains 23 to a shaft 24 journaled across 80 the top of the machine and provided at one end with a crank 25.

The gate 21 is approximately upright although it preferably overhangs the mixing trough as far as may be without interfering with the rotation of the mixing knives, and the bottom of the hopper is preferably formed at a greater angle than the angle of repose of granular material. This gate 21 serves with the ends 14 and slanting bottom 90 13 to define a kind of upwardly flaring trough which is divided into bins by movable upright partitions 26-26 of triangular shape. Secured to the end plates 14 and traversing this trough or hopper from end to end is a horizontal rigid rod 27 which holds said partitions against being removed or falling into the mixer, while permitting their ready adjustment lengthwise to define different proportions. Preferably each partition is provided on one side with a boss 28 having a set screw 29 therein by means of which the partition can be secured to the rod. I have also shown the upper rim of the plate 13 as outwardly turned and provided with spaced apertures 30 adapted for the reception of a pin 31 carried by a vertically movable button 32 pivoted to each of the partitions to assist in securing the same in place. The size of the entire hopper is 110 so chosen that its contents shall make one batch for the mixer, and the proportions of

the different ingredients are determined by the location of the partitions lengthwise of that hopper, after which it is merely necessary for the attendant to fill them levelful 5 with the proper materials, during the time that the previous batch is being worked over in the mixing trough.

Carried by the shaft 6 are a plurality of blades or knives adapted and arranged not 10 only to stir and mix the ingredients but also to eject the same upon raising the gate 16. According to the preferred form of my invention I employ four of such blades or knives, each having the shape of a segment 15 of a helix, each subtending between 90 and 180 degrees. Two of these blades 35, 36 are located close to the wall of the trough, one adjacent to each end thereof and of opposite inclination but overlapping at their 20 inner ends; the other two blades 37, 38 are spaced further from the wall of the trough, preferably so as to displace on each revolution approximately one-half of the charge which said trough contains. These latter 25 blades are likewise located, one adjacent to each end of the trough, and the inclination of each is opposite to that of the corresponding larger blade and also opposite to that of the other smaller blade. The small blades 30 also preferably overlap each other longitudinally a short distance, and the blades are rigidly affixed to suitable arms 40 carried by the shaft 6. The bottom of the trough is preferably reinforced by a plurality of 35 heavy rectangular metal bars 41, laid closely therein to constitute a lining for the plate 3.

The operation of the device is as follows: A charge of the different materials as measured in the different bins is introduced into 40 the trough by rotating the handle 25 in either direction so as to raise the door 21, the shaft and its blades being rotated in a direction to receive the material, that is in a clock-wise direction as observed in Figs. 45 1 and 3. The effect of each of the outer blades, 35, 36 after sweeping the charge into the trough is to transfer the same from one end of the trough to the other, but at each turn about half of the material is caught 50 by one of the inner blades 37, 38 and thrown over the shaft in the opposite longitudinal direction. Thus each time before one of the outer blades can produce a transfer of material lengthwise of the trough in one direction, the companion inner blade has removed one-half the material out of its path 55 and dropped it behind the outer blade in a position to meet the next moiety of material delivered by the other outer blade. This 60 causes the material to be constantly quartered and mixed with alternate quarters, while at the same time both sides of knives are tending to move the entire mass towards the outlet gate 16. The inclination of the 65 outer blades is such that rotation of the shaft

in the chosen direction shall tend to transfer the mass towards the opposite end of the machine, and these outer blades are preferably located on opposite sides of the shaft. As soon as mixing is complete, during which 70 time the attendant has had an opportunity to refill the bins, the gate 16 is raised by the rotation of the shaft 19, whereupon the action of the blades promptly ejects the entire charge into any suitable receptacle placed to receive the same after which the trough is immediately ready for a new charge. I 75 preferably provide no means for holding the gates open since in this way a workman can not conveniently open more than one at a time.

It will be understood that while it is desirable for the best operation of some features of my improved mixer that the blades be of such a nature as to exert a widely distributed sidewise lifting action upon the charge, that this effect can be secured with other detail shapes and constructions of blades than those herein shown; it will also be understood that the hopper and bin idea herein described can be utilized otherwise than as specifically illustrated, and is not restricted to use with mixing blades of this type or even with this kind of batch mixer; 80 also that the mixing blades herein described can be used with other forms of charging and discharging means; and in general that a great many changes can be made in details of the machine, so that I do not limit myself in any wise except as recited in my several claims which I desire may be construed, each independently of limitations contained in other claims.

Having thus described my invention what 85 I claim is:

1. In a concrete mixer the combination 90 with a mixing receptacle of the batch type of a hopper supported in a position to discharge into said receptacle, said hopper having an open top, a movable gate between said hopper and receptacle and one or more partitions traversing said hopper and defining a plurality of bins therein, all of said bins being closed by said gate.

2. In a concrete mixer the combination 95 with a mixing receptacle of the batch type of a hopper supported in a position to discharge into said receptacle, said hopper having an open top, a movable gate between said hopper and receptacle and one or more partitions traversing said hopper and defining a plurality of bins therein, all of said bins being closed by said gate and the capacity 100 of said hopper constituting one charge for said receptacle.

3. In a concrete mixer the combination 105 with a mixing receptacle of the batch type, of an open topped hopper having a capacity equal to one charge for said receptacle and supported in a position to discharge into 110

said receptacle, one or more movable upright partitions in said hopper terminating substantially at the top thereof, means for securing said partitions at different positions

5 in said hopper to define bins of different size, and a movable gate interposed between said hopper and receptacle and closing all said bins.

4. In a concrete mixer, the combination 10 with a mixing receptacle of the batch type of an open topped hopper having a slanting bottom forming one wall and a sliding gate forming the opposite wall, said gate being located between said hopper and receptacle, 15 and one or more upright partitions traversing said hopper crosswise to said gate and terminating at said gate and defining bins.

5. In a concrete mixer, the combination 20 with a mixing receptacle of the batch type of an open topped hopper having a slanting bottom forming one wall and a sliding gate forming the opposite wall, said gate being located between said hopper and receptacle, an upright partition traversing said hopper 25 crosswise to said gate, and means for securing said partition at any one of a plurality of positions along said hopper to define bins of desired size-relation.

6. In a concrete mixer, an open topped 30 casing having a slanting bottom and vertical ends, a substantially upright gate slidably mounted between said ends and defining with said ends and slanting bottom a trough-shaped hopper, crank means for raising and 35 lowering said gates, mixing apparatus on the downhill side of said gate, and a plurality of transverse partitions in said hopper defining bins, said gate constituting one side of each bin.

40 7. Concrete apparatus comprising the combination with a batch mixer of a batch hopper having therein one or more adjustable partitions defining bins of adjustable relative size, and means for dumping the entire contents of all said bins simultaneously 45 into the mixer.

8. The combination with a batch mixer 50 for concrete of an open topped hopper of a size to receive one batch of dry ingredients, one or more movable upright partitions therein defining bins of adjustable relative size, and means for dumping the entire contents of said hopper into said mixer.

9. A batch mixer for concrete comprising 55 a horizontal trough having closed ends, a horizontal shaft therein, said trough having a movable gate at one side, and blades car-

ried by said shaft, said blades having such inclination lengthwise as to lift the materials at least as high as said gate during the revolution of said shaft.

10. A batch mixer for concrete comprising 60 a horizontal trough having closed ends, a horizontal shaft therein, said trough having a movable gate at one side, and blades 65 carried by said shaft, each blade constituting the segment of a helix and different blades having different direction of inclination, whereby the mixture is transferred from end to end of said trough while said gate is 70 closed and is ejected sideways from said trough when said gate is opened.

11. In a concrete mixer, a horizontal 75 trough having vertical ends and an upright movable gate at each side, a charging hopper outside of one gate, a horizontal shaft in said trough, and blades having the shape of helical segments carried by said shaft and having such inclination as to eject the mixture through the other gate when the same 80 is opened.

12. A batch mixer for concrete having a stationary horizontal trough, a rotatable horizontal shaft therein, spiral blades carried by said shaft, a discharge outlet at one 85 side of the trough, and a movable gate for said outlet.

13. A batch mixer for concrete having a stationary horizontal trough, a rotatable horizontal shaft therein, spiral blades carried by said shaft, a charging inlet at one 90 side of said trough, a discharge outlet at the other side of said trough, and movable gates for said inlet and outlet.

14. A batch mixer for concrete having a 95 stationary horizontal trough, a rotatable horizontal shaft therein, spiral blades carried by said shaft, a charging inlet at one side of said trough, a discharge outlet at the other side of said trough, movable gates 100 for said inlet and outlet, and a charging hopper located adjacent to said inlet and having the inlet gate as one side thereof.

15. A batch mixer for concrete having a stationary horizontal trough, a rotatable 105 horizontal shaft therein, spiral blades carried by said shaft, a charging inlet at one side of said trough, a movable gate for said inlet, and a charging hopper located adjacent to said inlet and having the inlet gate 110 for one side thereof.

In testimony whereof I hereunto affix my signature.

CHARLES M. EBERLING.
